F. JARVIS.

LUMBER GUIDE.

APPLICATION FILED FEB. 23, 1918.

1,281,383.

Patented Oct. 15, 1918.

Inventor

F. JARVIS

By Watson E. Coleman

Attorney

UNITED STATES PATENT OFFICE.

FRANK JARVIS, OF OAKES, NORTH DAKOTA.

LUMBER-GUIDE.

1,281,383.

Specification of Letters Patent. Patented Oct. 15, 1918.

Application filed February 23, 1918. Serial No. 218,822.

To all whom it may concern:

Be it known that I, FRANK JARVIS, a citizen of the United States, residing at Oakes, in the county of Dickey and State of North Dakota, have invented certain new and useful Improvements in Lumber-Guides, of which the following is a specification, reference being had to the accompanying drawings.

10 This invention relates to certain improvements in lumber guides and has relation more particularly to a device of this general character especially designed and adapted for use in the piling of lumber and it is 15 an object of the invention to provide a device of this general character which may be readily and effectively supported by a lumber pile or the like and which is provided with means to facilitate the handling of the 20 planks or the like as they are applied to the pile.

It is also an object of the invention to provide a novel and improved device of this general character provided with means 25 whereby a support is afforded for the frame or other member generally employed to assure the proper slant of the pile as is generally preferred in lumber yards or the like.

The invention consists in the details of 30 construction and in the combination and arrangement of the several parts of my improved lumber guide whereby certain important advantages are attained and the device rendered simpler, less expensive and 35 otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein is illustrated a view in perspective of a lumber guide constructed in accordance with an embodiment 45 of my invention.

As disclosed in the accompanying drawings 50 1 denotes an elongated shank having its upper end portion provided with a socket 2 to receive the shank 3 of the forked member 4 whereby the member 4 is capable of rotary movement relative to the shank 1.

Rotatably supported by the forked member 4 is the roller 5 over which planks and 55 the like are adapted to be drawn in the forming of a lumber pile and by having the

forked member capable of rotary movement it will be at once self-evident that the roller may be arranged at an angle which best meets with the requirements of practice. 60

Slidably mounted upon the shank 1 is a pair of clamping arms 6 having their rear or heel portions operatively engaged by the screw member 7 which operates to cause their relative movements to engage a plank or the like as comprised in the pile and whereby the shank 1 is anchored in applied position. The upper working face of the lower arm 6 is serrated or otherwise roughened as at 8 to assure the proper gripping 70 action of such face upon the under surface of a board or the like while a working end portion of the upper arm 6 is slightly curved and tapered in order to facilitate its insertion in applied position and to increase the 75 efficiency of its contact with the upper surface of a plank or the like. Through the medium of the arms 6 the shank 1 is effectively supported by the pile with which it coacts. 80

Extending laterally from the shank 1 adjacent the opposite ends thereof are the arms 9 of predetermined length and which have threaded through their free end portions the screws 10 engageable with the adjacent face 85 of the pile whereby the shank 1 is effectively braced against the strain imposed thereupon as the planks or the like are engaged with and drawn over the roller 5. For this reason the arms 9 extend in the same general direction as the direction of travel of the planks or the like over the roller 5. Slidably engaged with the upper end portion of the shank 1 is a sleeve or collar 11 which is held 90 against movement laterally of said shank 12 through the medium of binding screws 12 or the like and carried by the sleeve or collar 11 are the oppositely directed arms 14 terminating in the upwardly directed extensions 15. The arms 14 serve as a support for 100 the upper end portion of a frame or the like which is generally employed to give to the lumber pile the desired slant and evenness which is preferred in lumber piles in the open, as in a lumber yard. 105

From the foregoing description it is thought to be obvious that a lumber guide constructed in accordance with my invention is particularly well adapted for use by reason of the convenience and facility with 110 which it may be assembled and operated and it will also be obvious that my invention is

susceptible of some change and modification without departing from the principles and spirit thereof and for this reason I do not wish to be understood as limiting myself to the precise arrangement and formation of the several parts herein shown in carrying out my invention in practice except as hereinafter claimed.

5 The forked member 4 is locked in desired position through the medium of a screw 15 threaded through the socket 2 which is engageable with the shank 3 of the fork.

I claim:

10 1. A lumber guide comprising a shank, a fork rotatably engaged with the upper end portion of the shank, a roller carried by the fork, a securing means carried by the shank intermediate the length thereof, and oppositely directed arms carried by the upper portion of the shank.

15 2. A lumber guide comprising a shank, a

Copies of this patent may be obtained for five cents each, by addressing the "Commissioner of Patents, Washington, D. C."

fork rotatably engaged with the upper end portion of the shank, a roller carried by the fork, securing means carried by the shank intermediate the length thereof, and oppositely directed arms carried by the upper portion of the shank, the extremities of said arms being provided with vertically directed extensions.

20 3. A lumber guide comprising a shank, a securing means carried by the shank intermediate the length thereof, bracing arms adjustably engaged with the shank at opposite sides of the securing means, and a member threaded through the outer extremity of 35 each of the bracing arms.

In testimony whereof I hereunto affix my signature in the presence of two witnesses.

FRANK JARVIS.
